(57) **CLAIM**

The ornamental design for a sports equipment drying apparatus, as shown and described.

DESCRIPTION

FIG. 1 is a perspective view of a sports equipment drying apparatus showing my new design;

FIG. 2 is a front view thereof;

FIG. 3 is a rear view thereof;

FIG. 4 is a right side view thereof;

FIG. 5 is a left side view thereof;

FIG. 6 is a plan view thereof; and,

FIG. 7 is an inverted plan view thereof.

The broken lines showing, for example, a fan/heater assembly housing, an electrical cord, tabs, pipe joints and air vents in FIGS. 1–7 are included for the purpose of illustrating environmental structure only and form no part of the claimed design.
